UNITED STATES PATENT OFFICE.

STEPHEN C. HOWARD, OF NEW YORK, N. Y.

DESIGN FOR A SLEEVE-BUTTON.

SPECIFICATION forming part of Design No. 13,291, dated September 12, 1882.

Application filed August 8, 1882. Term of patent 3½ years.

To all whom it may concern:

Be it known that I, STEPHEN C. HOWARD, a citizen of the United States, residing in the city of New York, in the county of New York and State of New York, have invented and produced a new and original Design for a Sleeve-Button, of which the following is a specification, reference being had to the accompanying drawing, forming part thereof.

10 The drawing represents in top view a sleeve-button embodying my novel design.

The base-piece A of the button, or that part which will be exposed outside the cuff, is a segmental spherical shell provided with a 15 series of facets, a. Surrounding and attached to this faceted base or shell is an initial letter, herein shown as "F," it being made of a dif-

ferent metal, that it may contrast in color with the color of the base or shell. A plain-faced letter mounted on a faceted ground forms a 20 strong contrast and novel and pretty design.

I claim—

The design for a sleeve-button herein shown and described, the same consisting of the faceted base or shell and initial letter thereon of 25 contrasting color.

In testimony whereof I have signed my name to this specification in the presence of two subscribing witnesses.

STEPHEN C. HOWARD.
